SIGHTING ATTACHMENT FOR GUNS

Filed Nov. 21, 1927

INVENTOR.
RICHARD W. KELM.

BY *Philip S. Hopkins*
ATTORNEYS.

UNITED STATES PATENT OFFICE.

RICHARD W. KELM, OF BINGHAMTON, NEW YORK.

SIGHTING ATTACHMENT FOR GUNS.

Application filed November 21, 1927. Serial No. 234,714.

My invention pertains generally to a sight attachment for guns and is particularly adapted for machine guns though not limited thereto, and has for a primary object 5 the provision of a means for enabling the operator to sight the gun for a given distance with the same accuracy at night or in the dark as in the day time.

Another object is to provide a sighting attachment of the general character described 10 which is simple in construction, easy of operation and which can be readily and effectively used by an unskilled operator.

Other objects and advantages in details of 15 construction and operation will be apparent as the description proceeds, reference now being had to the figures of the accompanying drawing wherein like reference numerals indicate like parts.

20 In the drawing:—

Figure 1 is a side view of a machine gun equipped with my sighting attachment.

Figure 2 is a detail perspective view of the attachment.

25 Figure 3 is a detail cross sectional view taken on the line 3—3 of Figure 2.

Figure 4 is a detail perspective view on an enlarged scale of one end of the attachment.

30 Figure 5 is a detail front view of the adjustable rear gun sight of the gun, with which my attachment cooperates.

Figure 6 is a detail cross sectional view taken on the line 6—6 of Figure 4.

35 The reference numeral 1 refers generally to a machine gun of any desired type provided with a barrel 2, handle 3, and a trigger 4, the gun being adjustably mounted by means of the pivoted bracket 5 upon the tripod or stand 6.

40 The foregoing elements are not shown or described in any detail as they form no part of my invention.

45 It is well known that in the use of a machine gun, the operator desiring or being instructed to adjust his gun to fire a given distance, first pivots the rear sight 7 upwardly to the position shown in Figure 1 and adjusts the slidable member 8 provided with the peep holes 9 and 10 to the proper 50 position with respect to the scales 11 on the sight 7. The slidable member 8 is usually provided as shown with a relatively large and a relatively small peep hole for different conditions of sighting. For instance, if the 55 small peep hole 10 is to be used and the gun

is to be adjusted for a thousand yards, the slidable member 8 is raised until the peep hole 10 is opposite the appropriate graduation on the scale 11 where it is suitably locked. The operator then sights through the peep hole 10 along the barrel 2 and over the front sight 12, adjusting the gun carriage on its pivot, for such alignment or sighting. Likewise, if the larger peep hole 9 is to be used, the member 8 is adjusted to bring the peep hole 9 opposite the desired point on the scale and the front sight 12 brought to alignment with the eye looking through such peep hole 9. This method of sighting is of course satisfactory in the day- 60 time but is useless at night and under darkening conditions when it is impossible to accurately line up the front sight 12 through the peep holes. In order therefore to make it possible to accurately sight the gun at 65 night, I have provided a sighting device 13 consisting of a relatively narrow flat strip in two sections, the adjoining ends of which are dove-tailed together as at 14 to permit longitudinal adjustment of the sections. The 70 front end of the device is provided with a slot 15 adapted to fit over the front sight 12 on the barrel 2 and the rear end of which is provided with a tapered point 16 adapted to engage in either of the peep holes 9 or 10. It 75 will be understood of course that the raising of the slidable member 8 on the sight 7 will make it necessary to slightly lengthen the member 13 by means of the dove-tail connection 14 of its sections in order to accommodate the point 16 within the peep hole. 80

85 Mounted slightly ahead of the point 16, I have provided the member 13 with a level 90 17 constructed in accordance with the well known type of level provided with a glass tube 17^a filled with a liquid 17^b and having an air bubble 18 for indicating when the same is positioned horizontally level. The air bubble is preferably visible from the top through the window 19 and from the sides 95 through the window 20 and the inner walls of the recess in which the level device is placed are painted with a luminous or radio active substance 21 whereby the air bubble 18 may be readily visible in the dark. 100

If desired, a small pocket flashlight 22 may be removably secured to the member 13, in addition to or instead of the luminously painted level. In such event, the spring clip 23 is provided, which retains the flash- 105 110

light in position and also supplies the light guard 24 for the level, to protect it against enemy eyes at night.

In the operation of my invention, the gunner first adjusts the sliding member 8 on the rear sight member 7 to the proper position with respect to the scale 11, hooks the front end of the sighting member 13 over the front sight 12 and places the point 16 at the 10 opposite end in the peep hole 9 or 10 whichever is being used. He then makes proper pivotal adjustment of the gun to bring the sighting device so positioned to a perfectly level and horizontal position, judging this 15 by watching the air bubble 18 in the level 17. It will be clear therefore that by this means, the gunner is enabled to set his sights for any given distance, whether at night or in the daytime and by the use of the sighting device 13 adjust his gun for firing at 20 such distance.

It will be understood of course that changes may be made in details of construction and arrangement of parts without departing from the spirit and scope of my invention. I do not limit myself therefore 25

to the exact form herein shown and described other than by the appended claims.

I claim:—

1. In combination with the front sight and a vertically adjustable rear sight of a gun, a sighting attachment extending between such sights and attachable thereto for adjustment with said rear sight, and a level for indicating the horizontal position of said attachment. 30

2. In combination with the front sight and a vertically adjustable rear sight of a gun, an extensible sighting attachment extending between said sights and attachable thereto for adjustment with said rear sight 40 and a level for indicating the horizontal position of said attachment.

3. A sighting attachment for guns comprising a longitudinally extensible member 45 provided at one end with a slot to receive a front sight of a gun and at the opposite end with a tapered point for engaging with a rear sight, and a level on said attachment for indicating the horizontal position of said attachment. 50

RICHARD W. KELM.
